[57] CLAIM

The ornamental design for a marine engine compartment heater, as shown and described.

DESCRIPTION

FIG. 1 is a perspective view of a first embodiment of a marine engine compartment heater showing my new design;

FIG. 2 is a front view of the marine engine compartment heater of FIG. 1;

FIG. 3 is a top view of the marine engine compartment heater of FIG. 1;

FIG. 4 is a side view of the marine engine compartment heater of FIG. 1, the opposite side being a mirror image of that shown;

FIG. 5 is a bottom view of the marine engine compartment heater of FIG. 1;

FIG. 6 is a perspective view of a second embodiment of a marine engine compartment heater showing my new design;

FIG. 7 is a front view of the marine engine compartment heater of FIG. 6;

FIG. 8 is a top view of the marine engine compartment heater of FIG. 6;

FIG. 9 is a side view of the marine engine compartment heater of FIG. 1, the opposite side being a mirror image of that shown; and,

FIG. 10 is a bottom view of the marine engine compartment heater of FIG. 6.
